SPOUT FOR LIQUID DISPENSING CANS

John T. Roth and Edgar W. Vahle, Dayton, Ohio,
assignors to The Huffman Manufacturing Company, Dayton, Ohio, a corporation of Ohio

Application October 26, 1932, Serial No. 639,552

15 Claims. (Cl. 221—26)

This invention relates to a spout for a liquid dispensing can and is designed more particularly for use on an oil measuring can of the type having a bottom discharge through a tilttable spout, such as are commonly used at automobile service stations.

Measuring cans of this type must usually be supported by the attendant or operator while the oil is being drained therefrom because the spouts are of such a character that they do not afford adequate support for the can. It is, however, very desirable that the measuring can should be self-supporting so as to permit the operator to attend to other matters while the oil is draining from the can.

One object of the present invention is to provide a dispensing can with a spout of such a character that it may be inserted in the filling opening of the receptacle in which the liquid is to be delivered and so engage with the edges of the filling opening that it will firmly support the can while the liquid is being drained therefrom.

A further object of the invention is to provide a spout of such a construction that when properly inserted in the filling opening it will be held against movement under the influence of the weight of the can and its contents.

A further object of the invention is to provide such a spout which will be very simple in construction and which may be produced at a low cost.

Other objects of the invention will appear as the device is described in detail.

In the accompanying drawing Fig. 1 is a side elevation of an oil can embodying our invention; Fig. 2 is a bottom plan view of a portion of the spout; Fig. 3 is a side elevation of a portion of the spout, partly in section, inserted in the filling opening of a receptacle; and Fig. 4 is a transverse section taken on the line 4—4 of Fig. 3.

In this drawing we have illustrated one embodiment of our invention and have shown the same as applied to an oil measuring can of a well known type but it will be understood that this particular embodiment has been chosen for the purpose of illustration only, that the invention may take various forms and may be applied to dispensing cans of various kinds.

In the particular embodiment here illustrated the dispensing can comprises a body 1 having a bottom 2 spaced some distance from the lower edge of the body, that portion of the body beneath the bottom forming a skirt 3 which constitutes a support for the can when the latter is not in use. The bottom of the can is provided

with a discharge opening which communicates with a discharge spout 4. This spout is rigid throughout its length and is pivotally connected at one end with the can. Preferably the pivotal connection for the spout is arranged within the skirt 3 and the spout has an offset portion 5 so arranged that the spout may be swung upwardly alongside of the can, in which position the offset portion 5 of the spout extends through an opening 6 in the skirt 3. The spout is supported in its upright position when the can is not in use and while it is being filled and carried to the point of discharge. When the oil is to be discharged the spout is moved downwardly to an inclined position, as shown in Fig. 1, and the discharge end of the spout inserted through the filling opening 7 of the receptacle 8 into which the oil is to be discharged, such as the filling opening or tube leading to the crank case of an automobile engine. When the spout is inserted in the opening and arranged in the inclined position shown the lower side of the spout will engage the outer edge of the opening at that side adjacent to the can and the upper side of the spout will engage the inner edge of the opening at that side of the opening opposite the side engaged by the lower portion of the spout. The spout is usually of sufficient strength to support the weight of the can and its contents but ordinarily it is substantially round in cross section and unless the weight of the can is very nicely balanced on the spout it will have a tendency to turn about a longitudinal axis or to twist about a transverse axis, either movement resulting in the upsetting of the can and the spilling of its contents.

To enable the spout to support the can in an upright position during the pouring operation the spout is provided with means to engage the receptacle and hold the spout against turning movement in the filling opening. Preferably, but not necessarily, this means is a part of the spout.

The spout here illustrated is so constructed that when inserted in the opening and properly engaged with the edges thereof it will be firmly held against turning or twisting movement or against longitudinal movement and will therefore support the weight of the can without attention on the part of the operator. For this purpose the lower side of the spout, as shown in Figs. 1 and 3, is provided with a substantially straight transverse portion to engage the outer edge of the filling opening. The filling opening is usually round and this lower surface of the spout is so shaped with relation thereto that it will engage

the curved edge of the opening at separated points which will firmly hold the spout against any tendency to turn about a longitudinal axis. To prevent the spout from twisting about a transverse axis the lower side thereof is provided with projections or transverse ribs arranged to receive between them the outer edge of the filling opening and to engage this edge at separated points. The engagement of the edge of the opening between the ribs or projections not only holds the spout against twisting or turning movement but also holds it against longitudinal movement. Consequently the spout is firmly held against all movement under the influence of the can and its contents, and the rigid spout will thus support the can in proper position while the oil is draining therefrom. Preferably a portion of the lower side of the spout adjacent to the discharge end thereof is flattened, as shown at 9, and this flattened portion is provided with a series of corrugations 10 which form the transverse ribs. In the present instance, a considerable number of corrugations have been shown to facilitate the proper engagement of the spout with the edge of the filling opening without requiring any careful adjustment on the part of the operator. The upper side of the spout may be of any suitable character but, in the present instance, is rounded or curved transversely to the length of the spout, as shown at 11, so that it will have relatively narrow contact with the edge of the filling opening. Consequently when the flattened portion, of the lower side of the spout, is in engagement with the outer edge of the filling opening at separated points, and the upper side of the spout is in engagement with the inner edge of the opening, at a relatively narrow point, the spout has a three point contact with the edges of the opening which results in a very firm support therefor. The spout may be formed in any suitable manner but, as here shown, is divided along the lateral edges thereof, as shown at 12, so that the body of the spout may be formed in two parts by means of suitable dies.

It is, of course, important that the can or container shall be held against tilting movement with relation to the spout during the pouring operation. The can as here shown is provided with a stop 14 arranged to engage the spout and limit the relative pivotal movements of the spout and the can. The pivotal connection being near the front of the can the center of gravity of the latter will be in the rear of the axis of that connection and the weight of the can and its contents will hold the stop in engagement with the spout and thus prevent the can from tilting in either direction with relation to the spout. Consequently when the spout has been inserted in the filling opening and is supported by the receptacle the can will be retained in an upright position and held positively against all tilting movement.

While we have shown and described one embodiment of our invention we wish it to be understood that we do not desire to be limited to the details thereof as various modifications may occur to a person skilled in the art.

Having now fully described our invention, what we claim as new and desire to secure by Letters Patent, is:

1. In a liquid pouring apparatus, a container, a spout of rigid material having one end connected with the lower portion of said container and having its other end portion adapted to extend through the filling opening of a receptacle, said spout being provided with means for sup-

portingly engaging the edge of said opening in such manner as to hold said spout against turning movement about a longitudinal axis.

2. In a liquid pouring apparatus, a container, a spout of rigid material having supporting connection with the lower portion of said container and adapted to extend through the filling opening of a receptacle and to have supporting engagement with said receptacle, said spout being provided with means to engage said receptacle in such a manner as to hold said spout against turning movement in said opening and thus cause said spout to support the container in an upright position.

3. In a liquid pouring apparatus, a container, a spout of rigid material having one end connected with the lower portion of said container and having its other end portion adapted to extend through the filling opening of a receptacle and to have supporting engagement with the wall of said opening, said spout being provided with means arranged to engage said receptacle at separated points so as to hold said spout against turning movement about a longitudinal axis.

4. In a liquid pouring apparatus, a container, a spout of rigid material having one end connected with the lower portion of said container and having its other end portion adapted to extend through the filling opening of a receptacle and to have supporting engagement with the wall of said opening, one side of said spout being shaped to engage said receptacle at separated points adjacent to said opening so as to hold said spout against turning movement about a longitudinal axis.

5. In a liquid pouring apparatus, a container, a spout of rigid material having one end connected with said container and having its other end portion adapted to extend through the filling opening of a receptacle in an inclined position with the upper and lower sides of the spout in engagement respectively with the lower and upper edges of said opening, one of said sides being shaped to engage the adjacent edge of said opening at separated points and the other of said sides being shaped to have a relatively narrow contact with the adjacent edge of said opening, thereby providing a three point support for said spout.

6. In a liquid pouring apparatus, a container, a spout of rigid material having one end connected with the lower portion of said container and adapted to support the same during the pouring operation, said spout having its other end portion adapted to extend through the filling opening of a receptacle and to have supporting engagement with the wall of said opening, said spout having a transverse shoulder arranged to engage said receptacle at points spaced apart transverse to said spout so as to hold said spout against turning movement in said opening.

7. In a liquid pouring apparatus, a container, a spout of rigid material having supporting connection with the lower portion of said container and adapted to extend through the filling opening of a receptacle with its upper and lower sides in supporting engagement respectively with the lower and upper edges of said opening, one of said sides of said spout having transverse corrugations to receive between them the adjacent edge of said opening and hold said spout against longitudinal movement in said opening, one of said corrugations being adapted to engage said receptacle at points spaced apart transversely to said spout so as to hold the latter against turning movement in said opening.

8. In a liquid pouring apparatus, a container, a spout of rigid material having one end connected with the lower portion of said container and adapted to support the same during the pouring operation, said spout having its other end portion adapted to extend through the filling opening of a receptacle with the upper and lower sides of said spout in engagement respectively with the lower and upper edges of said opening, the lower side of said spout having a transverse shoulder to engage said receptacle at the upper edge of said opening in such a manner as to hold said spout against movement about its longitudinal axis. 5
- 10 9. In a liquid pouring apparatus, a container, a spout of rigid material having one end connected with said container and having its other end portion adapted to extend through the filling opening of a receptacle in an inclined position with the upper and lower sides of said spout in engagement with the respective edges of said opening, the lower side of said spout having a flattened portion provided with transverse ribs spaced apart lengthwise of said spout to receive 20
- 25 between them the outer edge of said opening at one side of the latter, the upper side of said spout having its end portion curved transversely to said spout to engage the inner edge of said opening at the other side thereof.
- 30 10. In a liquid pouring apparatus, a container, a spout of rigid material having one end connected with the lower portion of said container and having its other end portion adapted to extend through the filling opening of a receptacle, 35 said spout and said container being provided with associated means for engaging the receptacle being filled in such a manner as to hold said spout against turning movement about a longitudinal axis and said container against tilting movement. 40
11. In a liquid pouring apparatus, a container, a spout of rigid material pivotally connected with the lower portion of said container, means for limiting the relative pivotal movement of the 45 spout and container in one direction, said means being so arranged that when in use said container and said spout will be urged into adjusted positions by gravity, the discharge end of said spout being adapted to extend through the filling opening of a receptacle, and means carried by said 50
- spout and cooperating with said receptacle in such a manner as to hold said spout and container against tilting movement in any direction. 5
12. In a liquid pouring apparatus, a container, a spout of rigid material having one end connected with the lower portion of said container and having its other end portion adapted to extend through the filling opening of a receptacle, said spout being provided with means for supportingly engaging the edge of said opening in such a manner as to hold said spout against slippage in the direction of its length and against rotation about a longitudinal axis. 80
13. In a liquid pouring apparatus, a container, a spout of rigid material having one end connected with the lower portion of said container and having its other end portion adapted to extend through the filling opening of a receptacle, said spout being provided with means for supportingly engaging the edge of said opening with sufficient contact in the aggregate to hold said spout against rotation about its longitudinal axis. 85
14. In a liquid pouring apparatus, a container, a spout of rigid material having supporting connection with the lower portion of said container and adapted to extend through the filling opening of a receptacle with the upper and lower sides of said spout in engagement with the respective edges of said opening, said spout having means to hold the same against longitudinal movement in 100 said opening and one side of said spout having its engaging surface in a substantially straight line transverse to said spout to hold said spout against turning movement in said opening.
15. In a liquid pouring apparatus, a container, a spout of rigid material having supporting connection with the lower portion of said container and adapted to extend through the filling opening of a receptacle with the upper and lower sides of said spout in engagement with the respective edges 110 of said opening, one of said sides having a projection to engage an edge of said opening and hold said spout against longitudinal movement and one of said sides having its surface shaped to engage an edge of said opening in such a manner as to 115 hold said spout against rotation about its longitudinal axis. 120
